(57) **CLAIM**

The ornamental design for a wireless communication device, as shown and described.

DESCRIPTION

FIG. 1 is a front perspective view of a wireless communication device showing our new design;

FIG. 2 is a front elevation thereof;

FIG. 3 is a rear elevation thereof;

FIG. 4 is a top plan view thereof;

FIG. 5 is a bottom plan view thereof;

FIG. 6 is a right side elevation thereof; and,

FIG. 7 is a left side elevation thereof.

The broken lines are used in the drawings to define boundaries of the claimed design and form no part of what is claimed.

UNITED STATES PATENT AND TRADEMARK OFFICE
CERTIFICATE OF CORRECTION

PATENT NO. : Des. 515,077 S
APPLICATION NO. : 29/212294
DATED : February 14, 2006
INVENTOR(S) : Ryan M. Nilsen et al.

Page 1 of 3

It is certified that error appears in the above-identified patent and that said Letters Patent is hereby corrected as shown below:

The title page should be deleted and substitute therefore the attached title page.

In the drawings:

Delete Fig. 1 and substitute therefore Fig. 1 as shown on the attached page.

Signed and Sealed this

Seventeenth Day of October, 2006

A handwritten signature in black ink, appearing to read "Jon W. Dudas". The signature is written in a cursive style with a large, stylized "J" and "W".

JON W. DUDAS
Director of the United States Patent and Trademark Office
